TO P. H. MURPHY COMPANY, OF PARNASSUS, PENNSYLVANIA, A CORPORATION
OF PENNSYLVANIA.

CAR.

1,087,407.

Specification of Letters Patent. Patented Feb. 17, 1914.

Application filed May 22, 1912. Serial No. 698,956.

To all whom it may concern:

Be it known that I, JOHN J. TATUM, a citizen of the United States, residing at Baltimore, in the State of Maryland, have invented certain new and useful Improvements in Cars, of which the following is a specification.

The object of my invention is to so construct a car roof that the individual roof sheets are free to move relatively to each other without tearing under the strains and stresses to which a roof is subjected owing to the "weaving" of the car in transit, and at the same time maintain water tight joints 15 between the sheets and between the sheets and the flashing at the eaves of the car.

A further object of my invention is to have the roof sheets extend over the eaves of the car onto the side thereof, but form 20 a loose joint with the flashing along a line short of the eaves of the car; and with these and minor objects in view, my invention consists of the parts and combination of parts as will be hereinafter pointed out.

25 In the drawing, Figure 1 is a perspective view of a car, broken away, embodying my invention; Fig. 2 is an enlarged detail sectional view, and Fig. 3 is a perspective view of a roof sheet constructed according to my 30 invention.

The reference numeral 1 represents the side plate, 2 the side sheathing, 3 the car line, 4 the roof sheathing, 5 the fascia, and 35 6 the side post of a car which may be of any approved construction. I prefer that the fascia be constructed with a lower thickened base as shown, because it is adapted to protect the fascia and the outer ends of the roof sheet from being 40 damaged by "cornering" or "side wiping", but of course it will be understood that this particular construction of fascia is not necessary to the successful use of my present invention.

45 The flashing 7 is secured to the fascia or side wall of the car by nails or any other suitable fastening and extends onto the roof of the car back from the eaves, covering the joint between the side plate, the side sheathing and the fascia, and is rebent upwardly 50 as at 8, the rebent portion being spaced from the body portion of the flashing.

The roof sheets 9 are rebent under intermediate their ends along a line short of the 55 eaves of the car to form an open hook-like

member 10 spaced from the under face of the roof sheet, the outer end 11 of the sheet extending down over the eaves of the car and overlying the flashing as shown to prevent water, snow and cinders entering between the portion 11 and the flashing. In the event of water being blown between the flashing and the portion 11 of the roof sheet, it will be prevented from passing under the main body of the roof sheet by 60 coming into contact with the rebend 8 of the flashing which acts as a dam to prevent the water from further inward movement, and together with the pitch of the car roof will cause the water to run back over the eaves 70 of the car. The hook 10 of the roof sheet, the rebent portion 8 of the flashing and the main body of the roof sheet are spaced from each other as shown, to prevent water, etc., from "creeping" from one to the other, 75 thus effectually preventing it from getting between the roof sheets and the roof sheathing 4 and entering the car and damaging the contents thereof.

The joint between the flashing and the roof sheets is a loose one, as will be seen from the drawing, which permits the sheets to move longitudinally of the car, but at the same time securely anchors them to the car along a line short of the eaves of the car. 80 The side edges of adjacent roof sheets are joined together by a loose joint short of the eaves of the car as shown, whereby the sheets are free to move transversely of the car. As will be seen from the drawing, 85 while I extend the ends of the roof sheets over the eaves of the car, they are secured by a loose joint to the car short of the eaves, so that in the event of the flashing becoming 90 damaged, the end 11 of the roof sheet constitutes a waterproof covering over the joints between the side plate, side sheathing and the fascia. The portion 11 of the sheet being superimposed over the flashing will naturally receive snow, rain, etc., and in 95 the event of a high wind, the snow, rain, etc., will be blown under the underbent portion of the sheet, but will be prevented from entering the car as the metal is continuous from one end of the sheet to the other including the under bent portion. Thus it 100 will be seen that the loose joint between the roof sheets and the flashing is protected against the elements by the construction of the sheet. By forming the loose joint be-

tween the flashing and the roof sheets short of the eaves of the car, it is more fully protected against rupture, than it would be if it were on the side of the car or at the eaves.

5 I claim:—

1. In a car, the combination with the roof sub-structure, of roof sheet having a return under bend short of its outer ends, said outer ends being bent down over the eaves of the 10 car, and a flashing extending under the roof sheet and terminating at its inner end in an upper return bend constructed to engage the return under bend of the roof sheet and form a loose joint therewith.
- 15 2. A car roof comprising roof sheets, the outer end of each of which is rebent on the underside to form an inwardly opening pocket and thence rebent outwardly and downwardly over the eaves of the car, and 20 a flashing mounted on the side of the car and bent over on top of the car with its inner end rebent on the upper side and interlocking with said pocket.
- 25 3. A car roof comprising roof sheets, the outer end of each of which is rebent under short of the eaves of the car to form an open hook spaced from the under face of the roof sheet, the end portion of the sheet be-

yond the hook being extended across the fascia and overlying the flashing, said flashing being secured to the fascia and extending under the roofing sheets and rebent to form a hook interlocking with said open hook on the sheet.

30 4. A car roof comprising roof sheets, the outer end portion of each of which is rebent under short of the eaves of the car to form a hook spaced from the under face of the roof sheet, said portion being rebent under the hook and extended across the top of the car wall and bent down on the side of said wall, and a flashing secured to the side of the wall and extending under the roofing sheet and rebent at its inner end to form a hook interlocking with the hook on the sheet.

40 5. A car roof sheet bent under and thence forwardly in the direction of length of the sheet, the outer edge of the sheet being bent downwardly and constructed to overlie a flashing on the side of a car.

45 In testimony whereof I affix my signature in presence of two witnesses.

JOHN J. TATUM.
